RAILWAY REFRIGERATOR CAR

Ralph B. Winship, Montreal, Quebec, Canada

Application April 28, 1939, Serial No. 270,576

7 Claims. (Cl. 62—15)

My invention relates to improvements in construction of insulated refrigerator cars in which metallic framing of the car body supports the insulated walls, roof and floor.

5 An object of my invention is to limit the transfer of heat between the car body metallic framing and the underframe of the car. In the present conventional refrigerator car it is common to either have the metallic framing outside of the 10 wall insulation or to intermittently break the wall insulation and apply same in panels having the metallic side framing members interposed between the insulation panels. I propose placing the metallic framing inside of the car body exposed to the interior of the car and applying the 15 wall and floor insulation outside of the metallic framing.

Another object of my invention is to provide 20 means for applying the car body insulation without a break between the wall and floor portions. By placing the metallic framing of the car wholly within the car body this is made possible.

Another object of my invention is to reduce 25 the wall thickness of the car, particularly in refrigerator cars of the so-called top bunker type, wherein flues or ducts are constructed within the car wall to provide communicating means between refrigerant and lading space. In the present conventional car the installation of such ducts necessarily increases the wall thickness. By placing 30 the car body metallic framing wholly within the car body I obtain space for ducts between the vertical members of the framing without increasing the thickness of the car wall.

35 Another object of my invention, particularly in refrigerator cars of the so-called top bunker type, is to place the car body metallic framing wholly within the car body thereby providing a support for refrigerant containers under the car roof. In the present conventional car of this type having 40 external metallic framing it is customary to provide a separate framing to support refrigerant containers. With my improved construction the necessity for independent framing is eliminated.

45 Another object of my invention is to position the metallic framework of the car body between the insulation and the lading space thereby permitting the floor rack hinging means to be secured directly to the car body framing.

50 Another object is to provide an internal metallic framework for supporting meat racks.

Other objects and advantages of my invention will be apparent from the following description and the accompanying drawings.

55 In the drawings:

Fig. 1 shows a typical half cross section of a railway refrigerator car incorporating my improved method of supporting the car superstructure on the underframe.

Fig. 2 is a longitudinal sectional view taken on the plane of line 2—2 of Fig. 1.

Fig. 3 is a sectional view taken on the plane 3—3 of Fig. 1.

Fig. 4 is a fragmentary section through the end wall.

Fig. 5 is a sectional view taken on the plane of line 5—5 of Fig. 4 with the insulation removed.

Fig. 6 is a sectional view taken on the plane 6—6 of Fig. 4 with the insulation removed.

Fig. 7 is a perspective of my improvement.

My invention is adaptable to a refrigerator car having an insulated wall 2, an insulated roof 3, an insulated floor 4, a floor rack 5 above the insulated floor, and an air space 6 between the floor and floor rack.

A refrigerant container 8 is positioned near the roof 3 of the car and adjacent the side wall 2 of the car. A drain pipe 9 is preferably provided with means to discharge liquids, draining from the container 8 to the outside of the car. A hatch 25 opening 15 is provided preferably in the roof of the car above the refrigerant container 8 for filling it with a refrigerant or cleaning the container.

The refrigerant container 8 is supported on beams 30 16 which are attached to the steel side framing 11 of the car by means of gusset members 12. A drip pan 13 is positioned under container 8 and spaced away from the bottom thereof to provide an air flue 14 therebetween.

The steel side framing 11 comprises a metallic top member spaced apart from a metallic bottom member or side sill 17 and spaced apart metallic posts 18 having their upper and lower ends respectively rigidly secured to the top member 16 40 and side sill 17.

An insulated partition 19 is preferably provided on the inside of the posts 18 and spaced apart from the wall 2 to provide a vertical wall flue 20 which communicates with the air space 45 6 below the floor rack 5 and also communicates with the air flue 14 having contact with the refrigerant container 8. These air flues 20 are preferably separated into a plurality of vertical flues by the posts 18.

If desired a metallic plate 21 provided with stiffening means 22 may be used instead of the steel framing 11 of Fig. 1. This arrangement is shown in Fig. 4. The metallic plate 21 is preferable for an end wall 23 of the car as it is better 55

adapted to withstand the impact shocks caused by shifting lading than is a framed construction.

My improvement provides means to support the metallic framing 11 and/or the plate 21 and 5 also to space same above and away from the metallic transverse members 24 and center sill 25 of the car underframe 26.

The above said means of support comprises 10 preferably a plurality of short columns 27 having their bases rigidly secured to the underframe 26 and their tops rigidly secured to the framing 11 and/or the plate 21.

Fig. 7 shows the preferred form of my improvement consisting of a short hollow cylindrical column 27 having a flanged base 28 provided with holes 29 for riveting or bolting to 15 underframe transverse members 24 or center sill 25 and having a flanged top 30 provided with holes 31 for securing to sill 17 or flange 32 of 20 metallic plate 21. It sometimes may be desirable to have more than one column to a supporting unit. As indicated in Fig. 5 and Fig. 6 two or 25 more columns having common flanges top and bottom may be used.

26 While I have described a hollow cylindrical column as the preferred form, the column 27 may be solid or shaped other than cylindrical.

The insulation material 33 of the floor 4 extends under the sill 17 to meet the insulation material 34 of wall 2. With this arrangement 30 the columns 27 are completely surrounded by insulation and therefore the only transfer of heat from underframe 26 to framing 11 and/or plate 21 will be due to the conductivity of the columns.

35 As the cross sectional area of the columns is relatively small the heat transfer will be correspondingly limited.

If desired the drain pipe 9 may extend through 40 a hollow column 27 and cold liquid from the refrigerant container 8 allowed to gradually escape and thereby cool the column and retard the transfer of heat between underframe 26 and sill 17.

The preceding description and the accompanying 45 drawings illustrating the preferred form of the invention pertain particularly to refrigerator cars of the top bunker type. However my invention can be used to equal advantage in end bunker refrigerator cars. It is to be understood 50 that the invention is not limited to the specific details of construction shown and described as it is obvious that various modifications thereof, within the scope of the claims, will occur to persons skilled in the art.

55 The structure for supporting the refrigerant containers which is disclosed herein is claimed in my co-pending application Serial No. 216,732, filed June 30, 1938; the heating pipes disclosed herein are claimed in my co-pending application 60 Serial No. 270,573, filed April 28, 1939; and the side wall construction disclosed herein is claimed in my co-pending application Serial No. 270,571, filed April 28, 1939.

65 I claim:

1. In a refrigerator car having an insulated wall and an insulated floor, said wall having a metallic sill, the edge of the floor insulating material extending under said sill, a metallic underframe positioned below said floor and means 70 for supporting said sill on said underframe, said means comprising columns, the top ends of said columns rigidly secured to said sill and the bottom ends of said columns rigidly secured to said underframe, said columns being of small cross

sectional area thereby limiting the transfer of heat between said sill and said underframe.

2. In a refrigerator car having an insulated wall and an insulated floor, said wall having metallic framing comprising a metallic top member, metallic posts and a metallic sill exposed to the interior of the car, the edge of the floor insulating material extending under said sill, a metallic underframe positioned below said floor and means for supporting said sill on said underframe, said 10 means comprising short columns, the top ends of said columns rigidly secured to said sill and the bottom ends of said columns rigidly secured to said underframe, said columns being of small cross sectional area thereby limiting the transfer 15 of heat between the interior and exterior of the car.

3. In a refrigerator car having an insulated wall and an insulated floor, said wall having metallic framing comprising a metallic top member, metallic posts and a metallic sill exposed to the interior of the car, the edge of the floor insulating material extending under and in contact with said sill, a metallic underframe positioned below said floor and means for supporting 25 said sill on said underframe, said means comprising short columns, the top ends of said columns rigidly secured to said sill and the bottom ends of said columns rigidly secured to said underframe, said columns being of small cross sectional area and surrounded by the floor insulating material positioned below said sill thereby 30 limiting the transfer of heat between the interior and exterior of the car.

4. In a refrigerator car having an insulated 35 roof, a refrigerant container adjacent the roof, an insulated wall and an insulated floor, said wall having a metallic sill, the edge of the floor insulating material extending under said sill, a metallic underframe positioned below said floor and means for supporting said sill on said underframe, said means comprising hollow columns, the top ends of said columns rigidly secured to said sill and the bottom ends of said columns rigidly secured to said underframe, said columns being of small cross sectional area, and means for 40 cooling said columns, said cooling being accomplished by permitting liquid refrigerant to escape from said refrigerant container through conduits, said conduits extending through the 45 hollow columns and discharging outside of the car body thereby limiting the transfer of heat between the interior and exterior of the car.

5. In a refrigerator car having an insulated 55 roof, a refrigerant container adjacent the roof, an insulated wall and an insulated floor, said wall having metallic framing comprising a metallic top member, metallic posts and a metallic sill exposed to the interior of the car, the edge of the floor insulating material extending under 60 and in contact with said sill, a metallic underframe positioned below said floor and means for supporting said sill on said underframe, said means comprising short hollow columns, the top ends of said columns rigidly secured to said sill 65 and the bottom ends of said columns rigidly secured to said underframe, said columns being of small cross sectional area and surrounded by the floor insulating material positioned below said sill and means for cooling said columns, said cooling being accomplished by permitting liquid refrigerant to escape from said refrigerant container through conduits, said conduits extending through the hollow columns and discharging outside of the car body thereby limiting the 70

75

transfer of heat between the interior and exterior of the car.

6. In a refrigerator car body having insulated walls, roof and floor, metallic framing positioned between the insulation and the lading space in said car, a metallic underframe positioned below the car floor and means for supporting said metallic framing on said underframe, said means comprising short columns, the top ends of said columns rigidly secured to said metallic framing and the bottom ends of said columns rigidly secured to said underframe, said columns being of relatively small cross sectional area and surrounded by the insulating material of said floor thereby limiting the transfer of heat between the car body metallic framing and the metallic underframe.

7. In a refrigerator car body having insulated walls, roof and floor, metallic framing positioned between the insulation and the lading space in said car, a refrigerant container adjacent the

roof, said refrigerant container supported by said metallic framing, a foraminous rack spaced from the floor to support the lading and to form an air duct below the lading, communicating means to permit the flow of air from the refrigerant container to the space between floor and floor rack, said means consisting of a duct positioned between vertical members of said metallic framing, a metallic underframe positioned below the car floor and means for supporting said metallic framing on said underframe, said last mentioned means comprising short columns, the top ends of said columns rigidly secured to said metallic framing and the bottom ends of said columns rigidly secured to said underframe, said columns being of relatively small cross sectional area and surrounded by the insulating material of said floor thereby limiting the transfer of heat between the car body metallic framing and the metallic underframe.

RALPH B. WINSHIP.
